UNITED STATES PATENT OFFICE.

JOSEPH A. DIEFFENBACHER, OF YORK, NEBRASKA.

DESIGN FOR A DRY MEASURE.

SPECIFICATION forming part of Design No. 28,736, dated May 31, 1898.

Application filed May 11, 1897. Serial No. 636,111. Term of patent 14 years.

To all whom it may concern:

Be it known that I, JOSEPH A. DIEFFENBACHER, a citizen of the United States, residing at York, in the county of York and State of Nebraska, have invented and produced a new and original Design for Dry Measures; and I do hereby declare the following to be a full, clear, and exact description of the same, reference being had to the accompanying drawings, forming a part thereof.

My invention relates to the unitary design for a dry measure illustrated in the accompanying drawings, in which—

Figure 1 is a perspective view of a dry measure embodying my design, and Fig. 2 is a vertical longitudinal section of the same.

My invention consists, essentially, of the unitary design shown, which comprises a cylindrical sheet-metal vessel 1, formed at top and bottom with circumferential beaded edges 2 and 4 and provided contiguous to the said beaded edge 2 with concavo-convex crescent-shaped handles 5. The crescent-shaped bases of these handles have their central portions concealed and their outlines broken by the said bead 2.

On the vessel 1 is an annular or cylindrical shell 6 of relatively smaller diameter. This shell is formed at its inner end with an out-

turned annular shoulder or surrounding collar 3, at its outer end with a beaded edge 8, 30 and intermediate of its length with an annular circumferential V-shaped groove 7. The annular shell is also provided with concavo-convex crescent-shaped handles 5, arranged as shown. A circular diaphragm 9 extends 35 across between the vessel 1 and shell 6 and forms a continuation of the beaded edge 4. On this diaphragm rests the annular shoulder or collar 3, which is concentric with the beaded edge 4 and formed at regular intervals with 40 heads or bosses 3^a. The opposite ends of the vessel 1 and shell 6 are open and the said diaphragm is visible from the exterior and also on the interior of both the vessel and shell.

Having thus described my invention, what 45 I claim as new, and desire to secure by Letters Patent, is—

The unitary design for a dry measure, herein shown and described.

In testimony whereof I affix my signature 50 in presence of two witnesses.

JOSEPH A. DIEFFENBACHER.
